UNITED STATES PATENT OFFICE.

SPENCER HEATH, OF ELKRIDGE, MARYLAND.

AIRPLANE PROPELLER.

Application filed August 6, 1924. Serial No. 730,475.

To all whom it may concern:

Be it known that I, SPENCER HEATH, a citizen of the United States, residing at Elkridge, in the county of Howard and State of Maryland, have invented certain new and useful Improvements in Airplane Propellers, of which the following is a specification.

This invention relates to airplane propellers and has particular reference to propellers made of wood or other non-metallic material in which it is necessary to protect the propeller blades by metal sheathing covering those portions of the blades most exposed to wear.

The objects of this invention are to provide means for fitting the metal more closely and firmly to the wood, especially on its convex side, to provide more secure means for joining the metal at the edges of the blades and to provide more durable protection of the edges of the blade against damage or wear.

With these and other objects in view I have invented the improvements described in this specification and illustrated by the attached drawing, in which:

Figure 1 is a plan view;
Figure 2 is a section on line 2—2 of Fig. 1;
Figure 3 is a section on line 3—3 of Fig. 1; and

Figure 4 is a section showing the method of metal sheathing heretofore employed.

For ten or twelve years it has been the practice to attach the sheet metal to the blade faces by rivets or screws with the metal extending somewhat beyond the edges of the blades and to bend the metal over the edges of the wood in plain laps as shown in Fig. 4, the metal being held together only by solder between the portions lapped. Under this practice there are two special difficulties: First, in applying the metal and joining it at the edges of the blades there is no practicable means for stretching and drawing the metal tightly and smoothly over the surface of the wood, the consequence being that there is cushion-like effect between the rivets or screws and at the lapped edges the metal does not draw firmly down against the wood, thus making the edge of the propeller insubstantial and subject to dents. Second, the soldered lap joints frequently crystallize and give way under the intense vibration of 1500 to 2000 and upwards revolutions per minute.

To obviate these difficulties I use a double lock seam for joining the metal at the edges of the blades. This seam is clearly shown at numeral 10 in Figs. 1, 2 and 3. The metal is first secured to the wood in that portion remote from the part to be seamed as by the line of rivets 11 (with few or only temporary fastenings near the edge to be seamed). The edges of the upper and lower sheets of metal 12 and 13 are carried forward together in a straight line as shown by the dotted lines at 14 and 15, the lower sheet projecting further than the upper and turned back upon it as shown dotted at 16 to make a three-ply portion beyond the edge of the blade. This is called the first turning. The second turning consists in folding the three-ply dotted portion back against the upper portion 12, thus completing the lock joint as shown at 10. This second turning has the important effect of drawing and stretching the portions 12 and 13 tight and firm over the wood and bringing the seam itself hard up against the edge of the blade with the firm stiffness and protection of four thicknesses of metal instead of two.

In practice, the thickness of metal and the size of the seam 10 is much smaller than in my illustration so that the seam imbeds itself partially into the edge of the blade with little if any distortion of the general contour. This stretching and double locking seam has been found of itself sufficiently strong to hold but its strength can be further increased by running solder in between the folds of the seam, in which case the solder at the edge of the seam 17 further improves the contour.

On account of the metal crystallizing when put in single sheets, I prefer to apply the metal on each side of the blade in several sections in accordance with my U. S. Patent No. 1,339,886, and with overlapped edges as shown at 18 and 19 in Fig. 1.

The stretching and locking seam is of peculiar value as applied to the leading edge of the blade (which is most exposed to injury and wear) but when both edges of the blade where the metal is applied are considerably curved the stretching and locking seam is formed on both edges of the blade. However, where one edge is straight or nearly so I prefer making the tip section for both sides of the blade in one piece and bending it without a seam over the straight edge of the blade as shown at 20 in Figs. 1 and

3 and forming the lock seam along the other edge of the blade and around the end.

This bending without seam is most desired where the trailing edge of the blade is 5 the straight edge, the protective interlocking seam then being formed, as shown on the drawing, on the leading edge, which is the edge most subject to wear.

While I have described my invention as 10 relating to wooden blades protected by metal sheets it is to be understood as applying to any materials that can be manipulated in the general manner described.

Besides the advantages of close fitting 15 sheets and harder and more durable edges a further value of this method of sheathing lies in that fact that by it the sheathing can be adequately secured to the blades without employment of any solder in the seams this 20 not only making the work more economical but opening up the employment as blade sheathing of such materials as "duralumin" and other light and strong alloys or other desirable materials which it may not be 25 practicable to unite by soldered seams.

Having fully described my invention and the method of its practice, what I claim is:

1. A sheathed propeller blade including 30 sheet material applied to both sides of the blade and joined at the edge of the blade by a double turned seam providing four thicknesses of sheet material at the seamed portion.

2. A sheathed propeller blade including 35 sheet material applied to both sides of the blade and joined at the leading edge of the blade by a seam providing four thicknesses of the sheet material.

3. A sheathed propeller blade including 40 sheet material applied to both sides of the blade, the material being bent seamless over one edge of the blade and joined by a seam on the other edge of the blade.

4. A sheathed propeller blade including 45 sheet material applied to both sides of the blade, the material being bent seamless over that edge of the blade having the lesser exposure to injury and wear and being joined by a seam providing four thicknesses of the sheet material at that edge of the blade having 50 the greater exposure to injury and wear.

5. A sheathed propeller blade including 55 sectional sheet material applied to both sides of the blade and joined at the leading edge of the blade by a seam providing four thicknesses of the sheet material.

6. The method of sheathing propeller blades which consists in applying sheet material to both sides of the blades with the edges of said material projecting beyond 60 the edge of the blade, attaching the material to the blade at some distance from the projecting edges and doubling said edges together in such manner as to stretch the material between its attachment to the blade and its projecting edges and at the same time to form an interlocking seam.

7. A sheathed propeller blade including 65 sheet material applied to both sides of the blade and joined at the edge of the blade 70 by a folded seam providing a plurality of thicknesses of sheet material at the seamed portion.

In testimony whereof, I hereunto affix my signature.

SPENCER HEATH.
